COMBINED BRUSH HOLDER AND RAZOR
BLADE CONTAINER

Alban Russell Culmer, Woodbridge, England, assignor to Culmak Limited, Woodbridge, England, a British company

Application May 31, 1950, Serial No. 10,289
In Great Britain December 15, 1949

Term of patent 14 years

(Cl. D4—3)

To all whom it may concern:

Be it known that I, Alban Russell Culmer, a subject of the King of Great Britain, residing at Woodbridge, Suffolk, England, have invented a new, original, and ornamental Design for Combined Brush Holder and Razor Blade Container, of which the following is a specification, reference being had to the accompanying drawing, forming a part thereof.

Fig. 1 is a side elevational view of a combined brush holder and razor blade container, showing my new design;

Fig. 2 is a perspective view; and

Fig. 3 is a bottom plan view thereof.

I claim:

The ornamental design for a combined brush holder and razor blade container, as shown.

ALBAN RUSSELL CULMER.
